(Cl. D26—14)

To all whom it may concern:

Be it known, that we, Emmanuel C. Nicholides, a citizen of the United States, residing in the city, county, and State of New York, and Charles L. Metzler, a citizen of the United States, residing in Palisades Park, Bergen County, New Jersey, have invented a new, original, and ornamental Design for a Hearing Aid Apparatus, of which the following is a specification, reference being had to the accompanying drawing, forming a part thereof. In the drawing:

Figure 1 is a plan view of hearing aid apparatus embodying the new design;

Fig. 2 is a side elevation thereof; and

Fig. 3 is a front view.

We claim:

The ornamental design for a hearing aid ap-
paratus, substantially as shown.

EMMANUEL C. NICHOLIDES.
CHARLES L. METZLER.
